UNITED STATES PATENT OFFICE.

JULIUS EDWARD THIELSEN, EUGENE LOUIS GIROUX, AND HENRY WILLIAM DILG, OF PORTLAND, OREGON.

AMALGAMATING APPARATUS.

SPECIFICATION forming part of Letters Patent No. 337,535, dated March 9, 1886.

Application filed October 29, 1885. Serial No. 181,270. (No model.)

To all whom it may concern:

Be it known that we, JULIUS EDWARD THIELSEN, EUGENE LOUIS GIROUX, and HENRY WILLIAM DILG, citizens of the United States, residing at Portland, in the county of Multnomah and State of Oregon, have invented certain new and useful Improvements in Amalgamating Apparatus; and we do hereby declare the following to be a full, clear, and exact description of the Invention, such as will enable others skilled in the art to which it appertains to make and use the same.

Our invention relates to an improved apparatus for separating the precious metals from their ores, especially for saving and amalgamating placer gold.

The invention consists in the combination, with a sluiceway, of a pan-amalgamator formed with inlet and exit aprons and semicircular side troughs for retaining the gold and amalgam, while allowing the water and sand to escape.

It further consists in the combination, with such sluiceway and pan-amalgamator, of a cylindrical rotary screen and a series of riffles, and, finally, in certain details of construction, as hereinafter more fully set forth, and particularly defined by the claims at the end of this specification.

In the annexed drawings illustrating the invention, Figure 1 is a side view of our improved amalgamating apparatus, partly in section. Fig. 2 is a sectional side elevation of a rotary cylindrical screen with inclosed worm and adjacent ore-hopper. Fig. 3 is a perspective view of our improved pan-amalgamator. Fig. 4 is a plan view of the same. Fig. 5 is a vertical longitudinal section of the pan-amalgamator on the line $x-x$ of Fig. 4. Fig. 6 is a horizontal section of the pan-amalgamator on the line $y-y$ of Fig. 5. Fig. 7 is a sectional view of one of the riffles. Fig. 8 represents a modification in the manner of rotating the cylindrical screen. Fig. 9 is a vertical transverse section of the pan-amalgamator on the line $z-z$ of Fig. 5.

Referring to these drawings, the letter A designates a sluice-box or sluiceway of suitable construction. At a convenient point in

drical screen, B, which preferably consists of two metallic rings, a b , that support a wire-cloth covering of suitable mesh to pass the gold-bearing sand. One end of the cylindrical screen B receives the spout or lower mouth, c , of a hopper, C, through which the ore is fed. This hopper may be made in any approved form, of wood or metal, as preferred, and is so arranged that its mouth c enters the cylindrical screen at a point below its axis, as shown in Fig. 2. By referring to this figure it will also be seen that the wire-cloth projects beyond the ring a at that end of the screen, and so receives the mouth c of the hopper, thereby preventing any of the unseparated material from falling outside of the screen.

The hopper C and the axis or shaft D of the screen B are supported by the sluice-box A in any convenient manner, so that the screen will occupy a transverse position in the sluice-box with the hopper C at one end.

Within the cylindrical screen B, and extending from end to end, is a worm, d , that is fastened to the wire-cloth covering and to the rings a and b at each end. This worm 75 propels or conveys through the cylinder B, as the latter rotates, all stones, gravel, and unproductive material that is too coarse to pass the meshes of the wire-cloth. The unproductive material and the fine productive sand are thus readily separated. If desired, a spout, E, may be attached to the sluice-box at the discharge end of the cylindrical screen B, as shown in Fig. 8.

To the exterior of the cylindrical screen we prefer to attach a number of narrow longitudinal strips, e e , of sheet-iron or other suitable material. These strips will prevent the sluice-box from being choked by sand falling through the screen, and will give the sand a strong forward motion as it passes the meshes of the screen. It is obvious that the strips e e may be made perfectly plain and straight, or they may be given any desired shape and width to more perfectly fit them for serving also as paddles to assist in rotating the screen. Instead of rotating the cylindrical screen B by means of paddle-strips e e , it may have its shaft connected by belting f to the shaft of a paddle-wheel, F, located in the sluice-box, as

shown in Fig. 8. In this case the cylindrical rotary screen B may or may not be provided with the strips e, as preferred.

Located in the sluiceway, at a suitable point 5 below the revolving screen, is a pan-amalgamator, G, the construction of which is clearly shown in Figs. 3, 4, 5, and 6. This amalgamator may be made of copper, cast-iron, or other material, and consists of a dish or pan, 10 g, provided with a communicating semicircular trough, h, on each side. At the inlet end of the pan is a metallic plate or apron, i, and at the exit end is an upward and outward inclined apron or sieve, k, composed of amalgamated steel wire-cloth of fine mesh. The aprons i and k are supported by vertical longitudinal flanges m m, one on each side of the pan. These vertical flanges cross the side troughs, h h, where they intersect the pan, as shown in 15 Figs. 3 and 4, and are provided with suitable openings for the passage of sand and water.

A transverse wall, o, extends across the pan g beneath the inner edge of the wire apron k, as shown in Figs. 5 and 6. This end of the 20 pan g can therefore communicate with the side troughs, h h, only through the wire-mesh apron k, while the opposite end of the pan communicates directly with the side troughs which open into said pan beneath the inlet-25 apron i. The width of the amalgamating-pan corresponds with that of the sluice-box; but the bottom of its main portion is one or two inches lower, so as to form a depression for receiving and holding the amalgam. The 30 bottoms of the troughs h h are raised from half an inch to an inch above the bottom of the pan-body. They communicate with the pan by openings as large as the size of the troughs will permit, said openings being the 35 full width of the troughs, and extending from their bottoms to the under sides of the aprons. To correspond with these openings, the bottom of the amalgamator, under the aprons and opposite said openings, is raised to a level 40 with the troughs. It will be seen that the apron i and flanges m m protect the openings of the troughs at the inlet end of the pan, while the transverse wall o protects the openings at the opposite end. When the pan G is 45 in position, the inlet-apron i is on a level with the bottom of the sluice-box. The exit-apron k has its inner edge very nearly on a level with the inlet-apron, but gradually rises toward the outlet of the pan, as shown in Fig. 5. Beneath each apron is a triangular metallic block or casting, p p', preferably made 50 hollow and filled in with concrete or plaster-of-paris. These blocks are arranged with their pointed ends toward the pan, as shown in Fig. 6, and serve to induce a current through the troughs h and pan g in the direction of the arrows. The block p beneath the inlet-apron i extends from the bottom of the raised portion of the pan to the under side of said apron, but the block p' does not extend quite to the 55 under side of the wire exit-apron k, and has

its top beveled or inclined toward each side, as shown in Fig. 9.

The purpose of the troughs h h and aprons i k is to counteract any tendency of the amalgam being forced out of the pan g and into the sluice by the force of the current and the weight of the material received over the inlet-apron. It will be seen that as the water and sand flow from the pan g over the steel-wire 70 apron k the latter will permit the passage downward of water and amalgam, while excluding coarse sand, and the water and amalgam thus admitted through the wire-mesh apron will be deflected to each side by the 75 sloping top of the block p', and will flow back into the pan g through the side troughs, h h, the sides of the block p beneath the inlet-apron serving to direct the current into the pan. A gentle revolving current is thus induced, which facilitates the settling and retention of the amalgam.

In order to subject the escaping sand to the further and repeated action of an amalgamating agent, and more particularly to catch and 80 save any float-gold or any amalgam that may have passed across the pan G, one or more riffles, H, are arranged in the sluice-box, at a convenient distance below the pan-amalgamator and at suitable intervals, as shown in Fig. 85 1. These riffles are in the shape of pockets, composed of cast-iron or copper, and each is provided with an amalgamated partition, K, which reaches to within an inch or two of the bottom of the riffle, and in that way divides it 90 into two chambers. In the bottom of each riffle is placed a few pounds of quicksilver. The partitions K are supported in the riffles in any suitable manner, so as to be adjustable, as required, with relation to the quantity of quicksilver or amalgam in the riffle.

The sand and water enter the riffle at s, and, after having been subjected to the action of the amalgamating agent, the water and unproductive sand leave the riffle at t, as shown in Fig. 7. An opening, L, in the bottom of the 100 riffle affords a means of drawing off the amalgam at pleasure by simply withdrawing the plug that closes said opening.

It is apparent that by the peculiar construction of our pan-amalgamator, with its aprons, semicircular side troughs, and revolving currents of water and amalgam, a large saving of gold will be effected, especially in connection with the riffles and the rotary cylindrical 115 screen.

What we claim as our invention is—

1. In an amalgamating apparatus, the combination, with a sluice-box, of an amalgamating-pan having aprons i k and semicircular side troughs, h h, substantially as described.
2. In an amalgamating apparatus, the combination, with a sluiceway, of an amalgamating-pan having a vertical wall, o, at one end, side troughs, h h, communicating with the body of said pan, metallic inlet-apron i, and wire exit-apron k, substantially as described.

3. In an amalgamating apparatus, the combination, with a sluiceway, of an amalgamating-pan having side flanges, *m m*, vertical transverse wall *o*, semicircular side troughs, *h h*, aprons *i k*, and triangular blocks *p p'*, located beneath said aprons, substantially as described.

4. In an amalgamating apparatus, the combination, with a sluiceway, of an amalgamating-pan having a deep body, *g*, with communicating side troughs, *h h*, of less depth, and an inlet apron or plate, *i*, and exit-apron or sieve *k*, substantially as described.

5. In an amalgamating apparatus, the combination, with a sluice-box and a pan-amalgamator having a wire exit-apron, *k*, of a riffle, *H*, provided with an adjustable partition, *K*, substantially as described.

6. In an amalgamating apparatus, the combination of the sluice-box *A*, having riffles *H*,

the amalgamating-pan *G*, and the rotary cylindrical screen *B*, substantially as described.

7. In an amalgamating apparatus, the combination of the sluice-box *A*, the amalgamating-pan *G*, and the rotary cylindrical screen *B*, having paddles *e*, and inclosing a worm or conveyer, *d*, substantially as described.

8. In an amalgamating apparatus, the combination of the sluice-box *A*, the rotary cylindrical screen *B*, having a conveyer, *d*, the hopper *C*, and the amalgamating-pan *G*, substantially as described.

In testimony whereof we affix our signatures in presence of two witnesses.

JULIUS EDWARD THIELSEN.

EUGENE LOUIS GIROUX.

HENRY WILLIAM DILG.

Correction in Letters Patent No. 337,535.

It is hereby certified that the residence of the patentees in Letters Patent No. 337,535, granted March 9, 1886, upon the application of Julius Edward Thielsen, Eugene Louis Giroux, and Henry William Dilg, of Portland, Oregon, for an improvement in "Amalgamating Apparatus," was erroneously written in the grant "Portland, Maine," whereas said residence should have been written *Portland, Oregon*; and that the said Letters Patent should be read with this correction therein that the same may conform to the record of the case in the Patent Office.

Signed, countersigned, and sealed this 20th day of April, A. D. 1886.

[SEAL.]

H. L. MULDROW,
Acting Secretary of the Interior.
